UNITED STATES PATENT OFFICE.

HARRY F. SCHUMANN, OF LOS GATOS, CALIFORNIA.

CUSPIDOR.

1,113,057.

Specification of Letters Patent.

Patented Oct. 6, 1914.

Application filed April 11, 1914. Serial No. 831,149.

To all whom it may concern:

Be it known that I, HARRY F. SCHUMANN, citizen of the United States, residing at Los Gatos, in the county of Santa Clara and State of California, have invented certain new and useful Improvements in Cuspidors, of which the following is a specification.

This invention relates to new and useful improvements in flushing cuspidors, and has for its principal object to provide a means by 10 which the cuspidor may be relieved of its contents.

Another object of the invention is to provide a device which is to be connected to the 15 city water supply and sewerage system and provided with a chamber to form a flush tank for containing the water and holding the same under pressure.

A further object of the invention is to 20 provide a means whereby the flushing of the cuspidor may be controlled at the will of the user.

With these and other objects in view, the 25 invention consists in the novel combination and arrangement of parts which will be fully set forth in the following specification and accompanying drawings, in which,

Figure 1 is a side view in elevation of a 30 cuspidor constructed in accordance with this invention, and Fig. 2 is a transverse sectional view taken on line 2—2 of Fig. 1.

Referring now to the drawings by characters of reference, the numeral 1 designates as at 35 entirely a cuspidor constructed in accordance with this invention having the outwardly flared base 2 which is provided with the slot 3, through which the lever of the operating mechanism is adapted to extend.

The main body portion 1 is preferably 40 formed of the cylindrical wall 4 having its upper edge turned as at 5, the free edge of which is turned downwardly and inwardly as at 6 to form the passage 7, the use of which will be more fully hereinafter described.

Secured to the wall 4 at the point where the curved portion joins the wall, is provided the inwardly extending flange 8 which projects toward the free edge of the wall 6 50 and terminates in the funnel-shaped member 9, the reduced end of which terminates in the cylindrical extension 10 which is arranged to be connected to the sewerage system.

55 A suitable bottom 11 is provided and has formed centrally thereof the aperture 12

through which the cylindrical extension 10 of the funnel-shaped member is adapted to extend. This bottom 11 is also provided near its edge with the inlet opening 13 with which the supply pipe 14 communicates. Diametrically opposite the inlet opening is provided the outlet opening 15, the walls of which form the valve seat 16. A suitable pipe 17 is arranged to communicate with the outlet opening and an angular extension 18 is formed at the opposite end of the pipe and projects upwardly through the chamber 19 and communicates with the passage 7 as illustrated in Fig. 2.

A suitable valve 20 is arranged to seat on the valve seat 16 and close the opening whereby the flow of liquid through the pipe 17 may be controlled. Connected to the valve 20 is the rod 21 which extends through the stuffing box 22 and is provided at its lower extremity with the pivotal connection 26 by means of which the operating lever 27 is held in operative relation with the rod 21. Surrounding the rod 21 between the stuffing box 22 and the pivotal connection 26 is provided the expansion coil spring 28 which is arranged to exert downward pressure against the pivotal connection 26 to normally hold the valve 20 against the seat 16. The lever 27 is provided with the slot 29 which is arranged to receive the pin 30 carried by the depending bracket 31 which is secured in any suitable manner to the pipe 17. The end of the lever 27 opposite the pivotal connection 26 is extended as shown in Fig. 2 and terminates in the enlargement 32 which is arranged to form a foot pedal by means of which the operation of the valve may be controlled.

It will be apparent from the foregoing that in use the pipe 14 is connected to a water main in any suitable manner and the pipe 10 connected to the sewerage system. Upon turning on the water it will be apparent that the same will flow through the pipe 14 into the chamber 19 and compress the air within the chamber 19. Pressure is then applied to the portion 32 of the lever 27 which will cause said lever to rock on its pivotal connection and force the rod 21 upwardly thereby raising the valve 20 from the seat 16 and permitting the liquid contained within the chamber 19 to flow through the pipe 17 and angular extension 18 into the passage 7, from which it passes into the funnel-shaped portion of the cuspidor and

out through the drain pipe 10, thus removing the contents of the cuspidor without further manipulation.

While in the foregoing there has been shown and described the preferred embodiment of this invention, it is to be understood that such changes may be made in the combination and arrangement of parts as will fall within the spirit and scope of the invention as defined in the appended claim.

Having thus described my invention, I claim:

15 A device of the character described comprising a cylindrical outer casing, an in-turned portion at the upper edge of the casing, a downwardly and inwardly extending flange formed at the free edge of the in-turned portion, a flange within the cylin-

drical body portion and projecting inwardly, a funnel-shaped member formed at 20 the free edge of the flange, the reduced end of the funnel-shaped member terminating in a drain pipe, a bottom within the cylindrical casing, the bottom, cylindrical casing, and funnel shaped member forming a chamber, an inlet pipe, an outlet pipe connected to the bottom and communicating with the chamber, and means to control the flow of liquid through the cuspidor.

25 In testimony whereof I affix my signature 30 in presence of two witnesses.

HARRY F. SCHUMANN.

Witnesses:
